UNITED STATES PATENT OFFICE.

GEORG DEISENHOFER, OF MUNICH, GERMANY, ASSIGNOR TO THE FIRM
OF DEUTSCHE TELEPHONWERKE R. STOCK & CO., G. M. B. H., OF BER-
LIN, GERMANY.

FUSE.

No. 825,879.

Specification of Letters Patent.

Patented July 10, 1903.

Original application filed May 31, 1905, Serial No. 263,035. Divided and this application filed August 7, 1905. Serial No. 273,167.

To all whom it may concern:

Be it known that I, GEORG DEISENHOFER, a subject of the German Emperor, and a resident of Munich, in the Kingdom of Bavaria, 5 Germany, have invented new and useful Improvements in Fuses, of which the following is a specification.

The present application is a division of my former application for main distributors for telephone exchanges, filed May 31, 1905, Serial No. 263,035, for which United States Patent No. 801,186 has been issued under date of October 3, 1905.

The subject of the present invention is a 15 safety-fuse specially suitable for telephone exchanges which is constructed after the manner of a plug-contact in order to enable it to be conveniently connected to the conductor, particularly to enable it to be mounted 20 direct upon similarly-shaped clamps of main distributors in a telephone exchange.

The improved fuse comprises a special construction of the ordinary safety-fuse, in which a solder point is heated so strongly by 25 the current that the small soldered-on bar is torn away by the pull of a spring, and the current thereby interrupted. These fuses have hitherto usually been fastened between 30 distinct spring-strips fastened to the wall and were in consequence thereof subjected, according to the incidental bending of these strips, to a stronger or weaker pull, which in addition thereto in the usual arrangements 35 was not axial, but directed sidewise, so that very often a weakening of the fuse-pins, and consequently an unsafe tearing out thereof, was caused.

According to the present invention the separable members fusibly connected are disposed axially with relation to each other, and the pin which forms one of the separable members is provided with a spring which exerts pressure in the direction of the axis of 45 the pin and the tension of which is always uniform. The spring is so protected, as by a sheath, that it can never be bent, which in the fuses hitherto common is a frequent occurrence and whereby the working of the fuse is prejudiced.

50 The accompanying illustrative drawings show a safety-fuse of this kind, Figure 1 being a longitudinal, and Fig. 2 a transverse, section.

A base 1 of insulating material carries two

slotted lugs or projecting supports 2 and 3, in which is inserted the fuse, which consists in the usual way of a core 4, provided with a heating-coil 5 and a pin 6, axially disposed with relation to said core and fusibly connected therewith at one end by a suitable fusible material, such as solder. The pin 6 carries at its end a spring 7, which bears against the lug 3, while a collar 8 on the end of the core 4 takes up the pull of the spring. One end of the coil 5 is connected by a wire 9 to the hollow contact or metal sleeve 10, while its other end is connected to the pin 6, which in its turn is again connected by the spring 7 and a wire 11 to a second hollow contact or metal sleeve 12. The two sleeves 10 and 12 are pushed as plug-contacts onto pins 13 and 14, which are preferably split at the top, and these pins are connected with the conductors to be protected. The connection between the pins 13 and 14 is therefore made by the sleeve 10, the wire 9, the coil 5, the fuse-pin 6, the spring 7, the wire 11, and the sleeve 12.

If the current flowing through attains a strength dangerous to the conductors or to the apparatus, the coil 5 heats up the core 4 so highly that the connection between the pin 6 and the core 4, formed by soft solder, melts, whereupon the spring 7 draws the pin out of the core and interrupts the current.

The fuse, together with the spring, is preferably protected by means of a casing 15 of such conformation as to fit snugly around the projecting supports 2 and 3 and capable of sliding thereon and securely held in position.

Having now particularly described and ascertained the nature of the said invention and in what manner the same is to be performed, I declare that what I claim is—

1. In a safety-fuse the combination with a base member provided with projecting supports and hollow contacts carried by said base member, said contacts and supports being insulated from each other, of a heating-core interposed between said supports, a pin movably mounted on one of said supports and disposed axially of said core, a fusible connection between said pin and core, a spring exerting an axial pull on said pin, and a heating-coil for said core electrically connected at its respective ends to said contacts through said interposed pin, substantially as described.

2. In a safety-fuse the combination with a base of insulating material provided with projecting slotted supports and hollow contact members carried by said base, of a core interposed between said supports and supported at one end within the slot of one of said supports, a pin movably mounted in the slot of the other support and disposed axially of said core, a fusible connection between 10 said pin and the unsupported end of said core, a coil-spring surrounding said pin and interposed between the outer end of said pin and its support, and adapted to exert a direct axial pull on said pin, a heating-coil inclosing said core, electrically connected at one end with said pin and at its other end with one of said contact members, and an electrical conductor interposed between the 40 other of said contact members and said spring, substantially as described. 35
3. In a safety-fuse the combination with a base of insulating material provided on one face with a pair of projecting slotted supports and on its opposite face with a pair of recesses and hollow contact members embedded in said recesses, of a heating-core mounted at 25 one end in the slot of one of said supports and at its other end disposed adjacent said other support and provided with a recess, a pin mounted in the slot of said other support and disposed within the recess of said core, fusible material embedding said end of the pin within 30 said recessed core, said core and pin being axially disposed relatively to each other and at right angles to said contact members, a
- coil-spring interposed between the outer end of said pin and its support and adapted to exert a direct axial pull on said pin, a heating-coil inclosing said core, electrically connected at one end with said pin and at its other end with one of said contact members, and an electrical conductor interposed between the 40 other of said contact members and said spring, substantially as described. 40
4. In a safety-fuse the combination with a base member provided with projecting supports and hollow contacts carried by said base member, said contacts and supports being insulated from each other, of a core and pin fusibly connected and mounted on said supports, a coil-spring surrounding said pin and interposed between the outer end thereof 50 and its support, a heating-coil surrounding said core, electrically connected at its respective ends to said contacts through said interposed pin, and a casing coöperating with said base member and said projecting supports to 55 slide thereon and cover and protect said coil and spring and their coöperating parts, substantially as described. 50

In testimony whereof I have signed my name to this specification in the presence of 60 two subscribing witnesses.

GEORG DEISENHOFER.
